UNITED STATES PATENT OFFICE

149,600

DESIGN FOR A COIN-OPERATED RADIO
RECEIVER OR SIMILAR ARTICLE

Nathan Wind, New York, N. Y., assignor to Hotel
Radio Corporation, New York, N. Y., a corpora-
tion of New York

Application January 12, 1948, Serial No. 143,666

Term of patent 14 years

(Cl. D56—4)

To all whom it may concern:

Be it known that I, Nathan Wind, a citizen of the United States, residing in the Borough of Queens, county of Queens, State of New York, have invented a new, original, and ornamental Design for a Coin-Operated Radio Receiver or Similar Article, of which the following is a specification, reference being had to the accompanying drawing, forming part thereof, in which

Fig. 1 is a front perspective view of my design for a coin-operated radio receiver;

Fig. 2 is a rear perspective view.

The present application is a continuation in part of my copending application Serial No. D. 140,126 filed July 5, 1947.

The dominant features of my design are shown in the drawing in solid lines, and are characterized by widely rounded corners of substantially equal curvature extending along the upper front and lower side portions, the tuning indicator window conforming to the curvature of said upper front corner, and a substantially flush centrally disposed rectangular speaker grille in the front portion.

I claim:

The ornamental design for a coin-operated radio receiver or similar article, as shown and described.

NATHAN WIND.
